UNITED STATES PATENT OFFICE

LEOPOLD PODSZUS, OF BERLIN-CHARLOTTENBURG, GERMANY

CARBURETOR

Application filed August 1, 1927, Serial No. 209,803, and in Germany August 31, 1926.

My invention relates to carburetors, more particularly of the type in which a fuel valve is lifted by means of a suction controlled piston and the stroke of the piston is limited by 5 a check under the control of the air-inlet valve.

It is an object of my invention to enable the valve to be opened under no-load conditions.

10 To this end I provide means for adjusting the check so as to enable the fuel valve to perform a corresponding lift.

In the drawing accompanying this application a carburetor embodying my invention 15 is illustrated diagrammatically by way of example.

In the drawing

Fig. 1 is an elevation,

20 Fig. 2 is an end elevation of the carburetor viewed from the right in Fig. 1, its attaching flange being partly broken away,

Fig. 3 is a section on the line III—III in Fig. 2, and

25 Fig. 4 is a section on the line IV—IV in Fig. 3.

Referring now to the drawing, *a* is the casting of the carburetor and *a'* is a flange by which the carburetor is attached to the manifold of the engine, not shown, *c* is the casing 30 of the fuel supply valve *n*, which is secured to one side of the casing *a*, *c'* is a threaded nipple on the fuel valve casing *c* to which the fuel supply pipe, not shown, is connected, *h* is a perforated plug which is arranged on 35 one side of the casing *c* below the seat of the fuel valve *n* and through which a small supply of auxiliary air is drawn into a branch pipe *l* of a choke tube *b* through a passage *h'* below the valve *n*. The choke tube *b* is 40 open at both ends and provided with a perforated partition *b'* near the branch pipe *l*. *f* is the air inlet valve which is seated at *e* in the end of the casing *a* opposite the flange *a'*. The valve projects partly from the casing *a* and is adapted to slide in a cap *f'* 45 which is screwed on the casing *a* and equipped with a slotted guide *w'* for a pin *w* which projects from one side of the valve *f*. The valve is bored axially and adapted to 50 slide on the choke tube *b*, a Bowden cable *g'*

being secured to a tubular projection in the extension of the axial bore. *i'* is a tubular boss projecting on the inside of the cap *f'*; and *i* is a spring inserted between the valve *f* and the bottom of the cap *f'*.

55 *d* is a tapered lining in the casing *a* which partly surrounds the end of the choke tube *b*, *m* is an annular groove in the periphery of the lining, and *k* are slots connecting the inner face of the lining with the groove *m*. The inside diameter of the lining is selected 60 in proportion to the power of the engine.

65 A cavity *u'* is formed in the casing *c* below the fuel valve *n*, *u* is a cylindrical block which may be displaced in the cavity, *v* is a set screw by which the block is held in position, *t* is a pin in the block, and *o* is a blade which is pivoted on *t*. *p* is a stepped piston arranged in a second cavity of the casing *c* below that in which the blade *o* is arranged, 70 *r* is a perforated cap by which the chamber of the piston is closed, and *q* is a passage connecting the groove *m* in the lining *d* and the chamber of the piston *p*. The rod of the piston bears on the blade *o* from below.

75 *z* is an adjustable screw in a double-armed lever *s* which is fulcrumed on the cap *f'* at *y*. *x* is a cam which is fulcrumed in the lever *s* at *x'*, and *x''* is a screw which is inserted in an eye of the lever *s* and engages a slot 80 at the end of the cam so that the relative position of the cam and the lever *s* is varied by turning the screw *x''*. *s'* is a spring which is secured on the casing *c* and tends to hold the lever *s* against the pin *w* of the air inlet valve *f* which may be flattened where it is engaged by the cam.

85 The suction of the engine tends to raise the piston *p* and, through the medium of the blade *o*, to open the fuel valve *n*. The leverage intermediate the piston *p* and the valve *n* is varied by displacing the block *u* in its cavity. The object of this arrangement is to enable the proper leverage between these parts to be found by experimentally displacing the block *u*. By moving the block *u* to the right, that is, in the direction of the flange *a'*, the leverage in favor of the piston *p* is reduced, and, by moving the block *u* to the left, it is increased.

In operation, the fuel valve *n* is lifted through the medium of the piston *p* and the mechanism connected with the piston, allowing fuel from the valve *n* to enter the passage 5 *h'* below the valve where it is partly atomized by the air from the perforated plug *h* and ejected into the branch pipe *l* at the end of which the mixture is met, further atomized and thoroughly churned by the air which 10 flows in axial direction in the choke tube *b*, and the mixture is finally ejected into the tapered lining *d*.

The screw *z* and the parts connected with it, serve for placing the operation of the 15 piston *p* and the valve *n* under the control of the air inlet valve *f*. It will be understood that the screw *z* in the end of the lever *s* is reciprocated vertically when the valve *f* is displaced, and that the amount of such 20 reciprocation is regulated by adjusting the position of the cam *x* with respect to its lever *s*. The upward motion of the blade *o* is limited by the screw *z*. If it is desired to use the carburetor under no-load conditions, the 25 screw *z* is so adjusted in its lever *s* that its end is beyond reach of the blade *o* so that the piston *p* is able to effect a small lift of the valve *n*.

I wish it to be understood that I do not 30 desire to be limited to the exact details of construction shown and described for obvious modifications will occur to a person skilled in the art.

I claim:

- 35 1. A carburetor comprising a casing, a fuel valve and an air inlet valve in said casing, a lever fulcrumed on said casing at one end and operatively connected with said fuel valve, means for displacing the fulcrum of said lever, suction-controlled means independent of said air inlet valve operatively connected with said lever, the point at which said fuel valve is engaged by said lever being nearer to its fulcrum than the point 40 where said lever is engaged by said suction controlled means, and an adjustable stop operatively connected with said air inlet valve and adapted to check the movement of said lever.
- 45 2. A carburetor comprising a casing, a fuel valve and an air inlet valve in said casing, a lever fulcrumed on said casing at one end and operatively connected with said fuel valve, means for displacing the fulcrum of said lever, suction-controlled means independent of said air inlet valve operatively connected with said lever, the point at which said fuel valve is engaged by said lever being nearer to its fulcrum than the point where said 50 lever is engaged by said suction-controlled means, a pin operatively connected with said air inlet valve so as to move in unison therewith, a double-armed lever fulcrumed on said carburetor and adapted to be engaged by said pin, and an adjustable stop on said double-

armed lever adapted to check the movement of said first mentioned lever.

3. A carburetor comprising a casing, a fuel valve and an air inlet valve in said casing, a lever fulcrumed on said casing at one end and operatively connected with said fuel valve, means for displacing the fulcrum of said lever, suction-controlled means independent of said air inlet valve operatively connected with said lever, the point at which said fuel valve is engaged by said lever being nearer to its fulcrum than the point where said lever is engaged by said suction controlled means, a pin operatively connected with said air inlet valve so as to move in unison therewith, a double-armed lever fulcrumed on said carburetor, a cam on said double-armed lever adapted to be engaged by said pin, means for varying the position of said cam with respect to said double-armed lever, and an adjustable stop on said double-armed lever adapted to check the movement of said first mentioned lever.

4. A carburetor comprising a casing, a fuel valve and an air inlet valve in said casing, a lever fulcrumed on said casing at one end and operatively connected with said fuel valve, means for displacing the fulcrum of said lever, suction-controlled means independent of said air inlet valve operatively connected with said lever, and a tapered lining facing the engine end of said carburetor and defining an annular space with the wall of said carburetor, said carburetor having a passage connecting said space with said suction-controlled means.

5. A carburetor comprising a casing, a fuel valve and an air-inlet-valve in said casing, a lever fulcrumed on said casing at one end, means connected with said fuel valve for holding said valve engaged with one side of the lever, suction-controlled means independent of said air-inlet-valve, means operatively connected with said suction-controlled means and engaging the opposite side of the lever, and a check operatively connected with said air-inlet-valve so that its position with respect to said lever is varied in conformity with the position of said air-inlet-valve, said check being adapted to engage the same side 110 of the lever as said means connected with said fuel valve.

In testimony whereof I affix my signature.
LEOPOLD PODSZUS.
